UNITED STATES PATENT OFFICE.

ROBERT EVERITT, OF BROOKLYN, NEW YORK.

STEAM-PUMP.

SPECIFICATION forming part of Letters Patent No. 426,002, dated April 22, 1890.

Application filed March 11, 1889. Serial No. 302,871. (No model.)

To all whom it may concern:

Be it known that I, ROBERT EVERITT, of the city of Brooklyn, in the county of Kings and State of New York, have invented a new and useful Improvement in Steam-Pumps, of which the following is a specification.

My invention is applicable to all kinds of steam-pumps; but I have for the purpose of illustration selected a steam-actuated air-compressor, that being the kind of steam-pump to which the improvement is applicable with special advantage.

I will proceed to describe the improvement with reference to the accompanying drawings, and afterward point out its novelty in the claim.

Figure 1 in the drawings is a side view of an air-compressor embodying my improvement. Fig. 2 is a plan view of the steam-cylinders and connections, the air-compression cylinders and their supporting-frame being omitted. Fig. 3 represents a transverse section in the line $x-x$, Fig. 1.

Similar letters of reference designate corresponding parts in all the figures.

A designates a bed-plate, at opposite ends of which are supported the two horizontal steam-cylinders B B'.

C is a frame erected upon the bed-plate A and supporting the two horizontal air-compression or pump cylinders D D', which are parallel with the steam-cylinders, but at a considerable elevation above them. The two air-compression cylinders D D' are in line with each other and their piston-rods are connected together or there is one rod E common to both, the pistons being at opposite ends of the said rod.

The steam-cylinders B B' are more widely separated than the air-compression cylinders D D', and are longer than their pistons, may have a stroke longer than that of the air-compression pistons, and they are somewhat out of line with each other. Their piston-rods F F' are connected by means of two connecting-rods G G' with two cranks $a a'$ on a horizontal shaft H, arranged transversely to the cylinders in bearings b on the bed-plate A.

These cranks are set at an angle of ninety degrees to each other on the shaft. The

shaft is represented as provided with two fly-wheels I I.

J is a lever having a longer lower arm and a shorter upper arm, and having its fulcrum d supported in bearings in the frame C above the steam-cylinders and below the air-compression cylinders, the relative length of the said longer and shorter arms being in proportion to the relative lengths of the steam-cylinders B B' and the air-compression cylinders D D' and to the strokes of their respective pistons. The upper end of the said lever J is connected by two connecting-rods e, with a cross-head f on the piston-rod E. The lower end of the said lever is connected by a connecting-rod g with the crank a, to which the connecting piston-rod G and the steam piston-rod F are represented as also connected.

The steam-cylinders and the compression-cylinder may have any suitable systems of induction and eduction valves—for instance, such as are commonly employed in steam-engines and on air-compression cylinders—and I therefore have not thought it necessary in the illustration of my invention to show any valves or valve-gear.

By the arrangement of the steam-cylinders and their connections the compression-cylinders, the lever J, and the connections of the latter with the crank a, and the compressor piston-rod E the steam-pistons are caused to impart to the air-compression pistons a stroke shorter than that of the steam-pistons and to obtain a leverage over the air-pistons. By my arrangement a very effective compressor is obtained.

It is obvious that the same system of connections, consisting of the lever J, the connecting-rods e g, cranks a, and connecting-rod G between the piston-rod F of the steam-cylinder B and the piston-rod E of the compression-cylinder D, may be used without the steam-cylinder B' and its piston-rod F', connecting-rod G', and crank a', and without the compressor-cylinder D', and a complete compressor would thus be left having the most essential features of my invention.

What I claim as my invention, and desire to secure by Letters Patent, is—

The combination of the two horizontal steam-

cylinders B B' out of line with each other, the two pump-cylinders D D', arranged in line with each other and having a direct connection between their pistons, the cranks *a a'*, 5 the lever J, having a longer and a shorter arm, the latter of which is connected with the rod E of the pump-pistons, the rods G G', connecting the pistons of the steam-cylinders with the two cranks *a a'*, respectively, and

the connecting-rod g, connecting the crank *a* 10 with the longer arm of the said lever J, all substantially as and for the purpose herein described.

ROBERT EVERITT.
